UNITED STATES PATENT OFFICE

ERNEST VELASQUEZ, OF NEW ORLEANS, LOUISIANA

ELECTROMECHANICAL BOTTLE OPENER

Application filed August 28, 1931. Serial No. 560,045.

The invention relates to an automatic bottle opener and more particularly to an electromechanical bottle opener.

The primary object of the invention is the provision of a device of this character wherein a support accommodates a plurality of bottles and the covers or tops therefor being controlled on the closing of electric circuits having arranged therein electromagnets so that when a switch to the circuit of each cover or top control device is closed selectively a cover or top can be raised to open position, thus eliminating the manual raising or lowering of the cover or top for the opening of the selected bottle, the device being applicable for use in laboratories, dental offices, surgical quarters, or in any place where a number of bottles are to be used for access to the contents thereof, thereby relieving an attendant or person from this manual act of opening the bottles by hand, the switches for closing the circuit to operate electromagnets for controlling the opening of the covers or lids to the bottles being arranged conveniently to an attendant or person.

A further object of the invention is the provision of a device of this character, wherein the covers or tops of bottles will be automatically controlled for the opening and closing of such bottles selectively.

A still further object of the invention is the provision of a device of this character which is simple in construction, thoroughly reliable and efficient in operation, neat and attractive in appearance and inexpensive to manufacture and install.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:—

Figure 1 is a fragmentary elevation of an instrument stand of that type employed in dental offices showing the device constructed in accordance with the invention supported thereby and also diagrammatically the electric equipment in association therewith.

Figure 2 is a perspective view of the switch box with push button switches for controlling individually the respective circuits of the device.

Figure 3 is an enlarged vertical transverse sectional view showing in detail the electromagnet and by full lines the bottle cover or top in closed position and by dotted lines in raised or opening position.

Figure 4 is fragmentary top plan view of the bottle rack and adjunct parts.

Similar reference characters indicate corresponding parts throughout the several views in the drawings.

Referring to the drawings in detail, A designates a stand which is of conventional form and is in character an instrument stand for dental offices, while superimposed thereon is a bottle rack in the form of a base 10 having a row of bottles 11 supported thereby, each bottle being engaged in a seat 12 therefore provided in said base, which latter is preferably in the form of a block preferably made from wood although the same may be made from any other suitable material.

Rearwardly of each bottle 11 supported upon the base 10 is a vertical housing 13 in the upper portion of which is rotatably supported a pulley 14 over which is trained a chain 15, one end of which carries a weight 16, while the other end is connected with the movable core 17 of an electromagnet 18, this being arranged in an open electric circuit including the wires 19 which are connected in parallel with the electric house wiring circuit 20. In each circuit having the wires 19 is arranged a switch 21 manually closed through the medium of a push button 22,

these switches 21 being located within a switch box 23 carrying at its top the buttons 22 and this box is adapted to be conveniently placed upon a foundation so that the push button 22 can be actuated by foot. On closing the respective circuits including the wires 19 the cores 17 of the magnets 18 will be drawn thereinto on energizing said magnets so as to shift the chain 15 to rotate the pulley 14 against the resistance of the weight 16 carried by said chain.

Each pulley 14 has thereon an arm 24 carrying a lid or top 25 for the bottle 12 adjacent thereto, the cover or top 25 being normally in closing position upon the bottle and when the magnet 18 is energized and the core 17 drawn therein the cover or top 25 will be raised from the mouth of the bottle 12 to opening position, that is, from the position shown by full lines in Figure 3 to that shown by dotted lines in said Figure 3 of the drawings. When the magnet 18 is de-energized by the opening of the circuit thereto the weight 16 becomes active to reverse the movement of the chain 15 and thus the rotation of the pulley will lower the cover or top 25 onto the mouth of the bottle 12 for the closing thereof.

It will be readily seen that manual opening of the bottles is entirely eliminated as such bottles can be opened automatically through pressing a selective switch button 22 which closes the switch 21 and thus the circuit to a magnet 18 is closed for the automatic raising of the cover or top 25 from the mouth of the bottle under selection thereof so that access may be had to its contents and thereby relieving manual labor for this purpose.

The device is readily useful in laboratories, dental offices, surgical quarters, hospitals, or other like places or institutions.

The housing 13 has a rounded upper end 26 and this end is cutaway at 27 to accommodate the swing of the arm for the opening and closing of the cover or top 26 as will be obvious.

What is claimed is:—

1. In a device of the kind described, a base, a plurality of bottles on said base, a pulley for each bottle supported by said base, a chain trained over the pulley, a weight on one end of the chain, electromagnets arranged in the base and having movable cores connected with said chains, normally open electric circuits having arranged therein the magnets and normally open electric switches, a box for inclosing the switches and having push buttons controlling said switches, and covers connected with the pulleys and normally closing the bottles and automatically raised when the switches close the circuits for energizing the electromagnets to draw their cores therein.

2. In a device of the kind described, a plurality of bottles, covers for said bottles, a pul-

ley having an extension for each cover, means active on the pulleys for rotating the same, and electro-magnets arranged relative to the pulleys and adapted to be arranged in normally open electric circuits closed by switches, whereby the electromagnet will become energized for attracting said means for the opening selectively of the covers.

In testimony whereof I affix my signature.
